EMIL E. NOVOTNY, OF RIVERSIDE, ILLINOIS, AND HENRY G. SCHWERDTLE, OF PHILADELPHIA, PENNSYLVANIA, ASSIGNEES TO STOKES & SMITH COMPANY, OF SUMMERTALE, PENNSYLVANIA, A CORPORATION OF PENNSYLVANIA.

JOGGING MECHANISM FOR PRINTING-PRESSES.

1,260,017.

Specification of Letters Patent. Patented Mar. 19, 1918.

Application filed April 30, 1914. Serial No. 835,402.

To all whom it may concern:

Be it known that we, EMIL E. NOVOTNY and HENRY G. SCHWERDTLE, citizens of the United States, residing at Riverside, in the county of Cook and State of Illinois, and Philadelphia, State of Pennsylvania, respectively, have invented new and useful Improvements in Jogging Mechanism for Printing-Presses, of which the following is

10 a specification.

This invention relates to printing presses of the rapid rotary type, and particularly to sheet delivering mechanism therefor, and has for its object to provide in connection with the receiving table for the printed sheets a straightening mechanism for alining said sheets in an orderly pile, said mechanism operating to engage each sheet as it is delivered from the take-off, and 20 properly aline it with the pile of delivered sheets on the receiving table.

In the present embodiment of this invention, the sheet straightening mechanism, hereinafter called a "jogging" mechanism, or simply a "jogger" comprises a plurality of plates or boards, preferably three, that reciprocate flatwise toward and from three sides of the pile of printed sheets, and engage such edges of each sheet as delivered 30 that project beyond the sides of the pile and "jog" or push the sheet into alinement with the pile. A fixed plate or board is secured on the receiving table, against which the fourth side of the pile rests and against 35 which it is built up. The jogging mechanism is adjustable for sheets of all sizes within the capacity of the press, and little time is required to change said mechanism to suit any size sheet desired.

40 The invention consists in the general combination of parts and in those features hereinafter described, all of which contribute to produce an efficient jogging mechanism.

A preferred embodiment of my invention 45 will be particularly described in the following specification while the broad scope of my invention will be pointed out in the appended claims.

In the accompanying drawings,—.

50 Figure 1 is a plan view of the jogging mechanism in position for use.

Fig. 2 is a vertical longitudinal sectional

view of the same and so much of a printing press as is necessary to show its connection therewith.

55

Fig. 3 is a bottom plan view of the sheet receiving table with the jogging mechanism mounted thereon.

Fig. 4 is a cross-sectional view taken in a plane substantially parallel with the axes of 60 the cylinders.

Fig. 5 is a detail view of a modified form of jogger board.

Fig. 6 is an elevation partly broken away showing in detail a stop which constitutes 65 a feature of the invention.

I have preferred to describe the invention as applied to a high speed rotary press.

In the drawings, 10 indicates the frame of a printing press in the top of which is 70 mounted printing mechanism including a form cylinder 11, an impression cylinder 12, and a take-off 13, which in the present instance are arranged in parallel with their axes in a common horizontal plane. The 75 take-off 13 in the present form of the invention comprises a revolving skeleton frame made of a plurality of relatively narrow rings or semi-rings 9 spaced apart, each secured on arms radiating from a hub, 80 the several hubs being longitudinally and angularly adjustable upon a shaft 14. Each semi-ring 9 carries a gripper finger 15 to take-off or remove from the impression cylinder 12 the sheets after being printed and 85 deliver said sheets to a receiving table 16 disposed below and forward of the take-off frame 13. The receiving table 16 is preferably mounted in an inclined position, as shown in Fig. 2, the angle of inclination 90 being adjustable and in such relation to the take-off that when the gripper fingers 15 thereon are carried during its rotation to the lowest position, these fingers will be opened by a fixed cam in the usual manner 95 to release the sheets which float down upon the receiving table one at a time and there pile up. In order that the printed sheets as delivered may be gathered on the receiving table in an orderly well alined pile of 100

sheets, a straightening or jogging mechanism such as now to be described is provided for abutting the edges of each sheet as delivered and while floating toward the pile,

and for moving the edges of said sheets into accurate alinement with the sides of the pile of sheets.

This mechanism includes joggers which 5 move inwardly and outwardly while maintaining themselves parallel with the axis of the table so that they operate to aline the sheets in a pile on the table.

Pivottally mounted upon the top of the 10 inclined receiving table 16 near its lower edge is a fixed alining member preferably comprising a bracket or base member 17^a which may be moved along the table to suit the various sizes of sheets printed and af- 15 fixed in any adjusted position by a thumb-screw 18, passing through a base member 17^a. This bracket carries a yielding up-right stop or plate 17 preferably pivoted to it. A torsion spring 17^b normally maintains 20 the stop in an upright position, that is, projecting upwardly from its lower or pivoted end, but permits it to swing outwardly and downwardly to allow for the free removal of the pack or pile of printed sheets from 25 between the jogging boards presently to be described. Pivoted to rock on a pin or stud 29 projecting from the underside of the table substantially in the center thereof, is a three armed lever 20, one arm 21 of 30 which is adjustably connected to an eccentric rod 22 provided on one end with an eccentric strap 23 surrounding an eccentric 35 24 on a continuously running shaft 25 that rotates in unison with the shafts of the printing and impression cylinders and the take-off frame. The opposite end of the eccentric rod 22 passes through a sleeve 26 provided with horizontal trunnions 27 piv- 40 otally mounted in the ends of a yoke 28 from which the stud 29 extends upwardly through an opening in the arm 21. An op- 45 erating rod 30 has an eye 31 on one end pivottally mounted on the stud 29 and held thereon by a cotter-pin 32 that also holds 50 the yoke 28 connected to the arm 21. The arms 33 of the three-armed lever 20 ex- 55 tend in diametrically opposite directions perpendicular to the arm 21. Upon each arm 33 is pivoted an operating rod 30 similar to 60 the rod on the arm 21, said rods 30 each ex- 65 tending to and beyond one edge of the re- ceiving table 16 as shown in Figs. 1 and 3, and are each guided adjacent the edge of the table by an angle plate 34 affixed to the 70 underside of the table and provided each with an opening through which the res- 75 pective rods pass and reciprocate longi- tudinally as the three-armed lever is rocked by the eccentric. A slot 35 is formed in 80 the table over each rod 30 that extends from the edge of the table nearly to the center thereof, through each of which slots a stem 36 fastened on the lower edge of the jogger plate passes, said stems having open- 85 ings through their lower ends for the rods

30 on each of which a stem is adjustable longitudinally and fixed after adjustment has been obtained by a thumb-screw 38. Se- 70 cured to the inner side of each plate 37 is a jogger preferably in the form of a board 75 or plate 39, the inner face of which is bevelled or inclined outwardly at the top as at 39^a for a purpose shortly to be described. The jogger boards which are at the side and the stop plate or plates 17 inclose a rectangu- 80 lar space within which the printed sheets as delivered are piled against the said stop plate 17. And the upper edges of the joggers preferably project high enough so as to extend beyond the position of the sheet 85 when it comes off the take-off, (see Fig. 2.)

Extending across the frame above the upper end of the receiving table 16 and be- 90 low the take-off frame 13 is a fixed cross- 95 bar 40 to which one or more, preferably two, upstanding sheet engaging stop fingers 41, are adjustably secured, their upper ends ex- 100 tending between two of the rings or semi- rings of the take-off 13. These fingers form stops for the printed sheets and disengage 105 them from the take-off and its gripper fin- 110 gers 15. The parts are so timed that the gripper fingers 15 open just as the advanced edge of the sheet carried by the take-off frame and extending outwardly above the 115 pile of sheets on the table 16 and substan- 120 tially parallel therewith, contact with the stop fingers 41, thus not only arresting the forward movement of the sheet but actually causing the latter to rebound by such con- 125 tact so as to assume a position over the pile as more clearly shown in Fig. 2, while the gripper fingers and frame continue their rotation. The floating sheet being thus dis- 130 engaged from the take-off begins to settle on the receiving table or pile of sheets thereon, during which settlement, if out of line with the pile of sheets, the projecting edge or edges will be struck by the rapidly vibrat- 135 ing jogger board or boards and alined with the pile. Owing to the rapid operation of the press and the distance between the take- 140 off and the table 16, or pile of sheets there- 145 on, there will be several sheets floating above the pile of sheets and gradually descending 150 on the pile. These floating sheets being at different heights above the pile will have their edges at different distances from the inner walls of the jogger boards because of the outward inclination or level of the upper 155 parts of said boards, and therefore the high- 160 est sheet will not be subject to the full force of the blow of the board or boards owing to the lost motion between the board and the edge of the sheet. As the sheets descend 165 the force of the blows increase due to the increasing thickness of the boards and less- 170 ening of lost motion, but the sheets being nearer alinement from previous blows, this 175 increasing force does not tend to cramp or 180

crush the edges of the sheets which finally descend until past the inclined portions of the boards and are evenly alined directly upon the pile.

5 The jogger boards may be made as in Fig. 4 with the inner face of the board beveled at the top, or as in Fig. 5, with the entire upper portion of the board inclined outwardly. To assist the disengagement of the 10 sheets from the gripper fingers and cause said sheets to rebound and fall properly on the table 16, an adjustable block 42 is connected to the upper end of each stop finger 41 by a bolt and thumb nut 43, said bolt 15 passing through a slot in the finger to permit the block to be raised and lowered. The upper surface of the block is inclined downwardly as at 42^a toward the receiving table 20 that the sheet may be discharged quickly 20 therefrom and directed toward the pile of sheets thereon. The feed table 16 while normally stationary may be adjusted as desired to accommodate it for the work to be done and the size of sheets to be printed, and when 25 the position of the table is to be thus changed a bolt 44 that secures the eccentric rod 22 in the sleeve 26 is loosened to permit the rod adjusting itself to the changed conditions. The same adjustment is employed 30 when the positions of the jogger boards 39 are to be changed to suit sheets of different sizes. This adjustment will be supplemented when necessary by the individual adjustment of the jogger boards on the rods 30 35 by loosening the thumb nuts 38, and sliding the board longitudinally of its operating rod. In Fig. 4, the back jogger is omitted for the sake of clearness.

The revolving take-off 13 in the skeleton form shown is particularly well adapted 40 for the purposes of this press. The partial rings 9 are narrow and have only slight contact with the sheets, the latter therefore upon contacting with the fingers 41, are 45 thrown out straight by the momentum of the rapidly revolving take-off and are stopped and taken from the take-off in the space over the table, and so that they assume a position where they will fall properly 50 on the pile of printed sheets without relative sliding contact between the sheets such as would result in blurring or smearing and there is no tendency for the sheets to hug or lie close to the take-up which 55 would be the case if the surface of the latter was smooth and unbroken. By using the take-off to receive the sheets from the impression cylinder, the sheets are delivered 60 printed side up, and being jogged into alinement while floating in the air before falling 65 on the pile, the fresh ink is not smeared.

In the operation of the press, the sheets are disengaged from the take-off frame in a position inclined to the horizontal with 65 the depressed edge of the sheet disposed

toward the depressed edge or lower edge of the receiving table; due to the high speed of the parts, there are a number of sheets which are delivered in this way over the table, and which are simultaneously gravitating toward it. On account of the inclined position of the sheets, they tend to drift or float over against the stop 17 which is relatively fixed with respect to the operation of the joggers. Furthermore on account of the high speed of the press, the joggers will be reciprocated and engage a plurality of times with each sheet as it descends. In this way, the actual alinement of the sheet takes place in the air just over 80 the pile of sheets so that the sheets sink into place one on top of the other without any sliding action tending to produce blurring.

It is understood that as the sheets are disengaged from the take off, they are given a slight impetus in the direction of the depressed edge of the table so that as they gravitate downwardly, they float or volplane toward the stop 17. The side jogger boards 90 39^a project up beyond the position of the sheet as it is delivered from the take off. They extend substantially at right angles to the fixed alining member 17^a.

In the operation of the press the sheets 95 are fed as usual over the impression cylinder 12 and passing therebetween and the form cylinder 11 are printed, after which the printed sheets are transferred to the rotary take-off frame 13 and carried around 100 in the direction of the arrow, Fig. 2, and when the take-off frame is in the position shown in said figure the edge of the sheet engaged by the grippers 15 will strike the stop fingers 41 and said gripper fingers 105 opening at the same time will release the sheet which rebounds slightly and gradually settles down upon the receiving table 16 or the pile of sheets thereon. The jogger boards at this time are advancing in unison 110 toward the pile of sheets and should the newly printed sheet just dropped therebetween project beyond one or more sides of the pile, said boards will engage the edges 115 of said sheet and move it into alinement with the pile and against the stop plate 17, the boards being so adjusted that their inner limit of movement is defined by the sides of the pile of sheets; the boards then withdraw ready to receive the next sheet.

It is understood that the embodiment of the invention described above is only one of the many embodiments or forms the invention may take, and I do not wish to be limited in the practice of my invention nor 125 in my claims to the particular embodiment described.

What is claimed as new is,—

1. The combination with the sheet delivering mechanism of a press, of a support for 130

the delivered sheets so located below the delivery mechanism and relative thereto that a plurality of individual sheets will be simultaneously freely floating in the air on their way from the delivery mechanism to the support, and jogger mechanism associated with the support, and interposed between the latter and the delivery mechanism for producing a plurality of engagements with each floating sheet while such sheet is floating toward its position of rest upon the support.

2. In a printing press, the combination with a rotary-take-off frame mounted on a substantially horizontal axis, of a receiving table located beneath the frame and adapted to receive printed sheets from the take-off frame, a rear end jogger member located beneath the rotary take-off frame and disposed substantially in vertical alinement with the horizontal axis of the frame, a plurality of spaced side jogger members having the rear vertical ends thereof also lying in substantially the same vertical plane as the horizontal axis of the rotary take-off member, a front stop for the sheets mounted on a table, and means for reciprocating the jogger members to produce a plurality of reciprocations and engagements of the latter with the sheets while such sheets are floating in the air descending from the rotary take-off to the table.

3. In a printing press, the combination with a rotary take-off frame mounted on a substantially horizontal axis, of a sheet receiving table located beneath the frame and adapted to receive sheets descending from the rotary take-off, a rear end jogger board located beneath the rotary take-off and substantially in vertical alinement with the horizontal axis of the frame, a pair of side jogger boards spaced apart and arranged substantially in parallelism and with the upper edge portions thereof outwardly inclined relatively to each other, the rear vertical ends of said boards terminating at the vertical ends of the rear end jogger boards, a front stop for the sheets mounted upon the table forward of the side jogger boards and pivoted at its lower end to swing into and out of vertical position, and means for reciprocating the side and rear end jogger boards to engage the latter with the sheets descending from the rotary take-off frame to the table.

4. In a high speed printing press, in combination, printing mechanism, a receiving table adapted to hold a pile of sheets, means including a rotary take-off frame, for delivering the printed sheets from said printing mechanism over said table so that they will gravitate toward the latter, a plurality of joggers for engaging and alining the sheets into a pile on the table, including a pair of jogger boards extending upwardly beyond the position of the sheet when delivered from the press and mounted to reciprocate inwardly and outwardly at said table,

the upper inner face portion of said jogger boards being inclined outwardly relative to each other, and means for actuating said joggers to produce a plurality of reciprocations thereof and a plurality of engagements with each sheet while each sheet is descending to its position of rest upon the table.

5. In a high speed printing press, in combination, an inclined receiving table adapted to hold a pile of printed sheets, printing mechanism, means for delivering the sheets from the printing mechanism, in the space over said table and so they will gravitate toward the latter, said means including a rotary take-off frame, a fixed alining member on the depressed part of said table for alining the lower edges of said sheets, a pair of side jogger boards disposed substantially at right angles to said fixed member and extending beneath the rotary take-off frame, said jogger boards being of sufficient height to extend above the point of delivery of the sheets at the rotary take-off frame, said jogger boards being mounted to reciprocate inwardly and outwardly at the table for engaging and alining the sheets as they approach the table and means for actuating said joggers to produce a plurality of reciprocations and engagements thereof with each sheet while descending to its position of rest at the table.

6. In a high-speed printing press, in combination, an inclined receiving table adapted to hold a pile of printed sheets, printing mechanism, means for delivering the sheets from the printing mechanism in the space over said table and so that they will gravitate toward said table, a fixed alining member on the depressed part of said table for alining the lower edges of each sheet, a pair of side jogger boards disposed substantially at right angles to said fixed member, mounted to reciprocate inwardly and outwardly at said table for engaging and alining each sheet as it approaches the table, the upper edge portions of said boards extending above the point of delivery of the sheets by the sheet delivering means, and means for actuating said jogger boards to produce a plurality of reciprocations and engagements thereof with each sheet while descending to its position of rest at the table, and with the lower edge of the sheet against said fixed alining member, said jogger boards having inclined inner faces at their upper edge portions to engage the edge of the sheet.

7. In a printing press, in combination, printing mechanism, a table disposed in an inclined position, means, including a horizontally disposed rotary take-off, for delivering the sheets from said printing mechanism over said table in a position inclined to the horizontal, with the depressed edge of the sheet disposed toward the depressed edge of the table so that the sheet tends to

- gravitate toward the table and to shift side-
wise toward the depressed edge thereof, a
pair of side jogger boards extending above
the table and projecting beneath the rotary
5 take-off frame, and means for reciprocating
said joggers to cause the latter to engage the
edges of the sheets a plurality of times while
such sheets are floating in the air and aline
the sheets in a pile against the stop.
- 10 8. In a printing press, the combination
with a skeleton take-off frame, a receiving
table upon which the printed sheets are de-
livered from said frame and gathered into a
pile, and a stop plate or board on said
15 table against which one side of the sheets
abut, of a plurality of vibrating plates or
boards parallel with the edges of the sheets
with their inner faces inclined outwardly
movable in unison in straight lines to and
20 from the other three sides of the pile of
sheets to engage the edges of each sheet as
delivered and aline it upon said pile, and
means for adjusting the three plates or
boards relative to each other to accommodate
25 them to the size of sheet delivered.
9. In a printing press, the combination
with a skeleton take-off frame, a receiving
table upon which the printed sheets are de-
livered from said frame and gathered into a
30 pile, and a stop plate or board on said table
against which one side of the sheets abut, of
a plurality of vibrating plates or boards
with outwardly inclined faces arranged par-
allel with the edges of the sheets movable in
35 unison in straight lines to and from the
other three sides of the pile of sheets to en-
gage the edge of each sheet as delivered and
aline it upon the pile of sheets and means
for independently adjusting each plate or
40 board relative to the other plates or boards
to accommodate the size of sheet delivered.
10. As a means for alining the sheets de-
livered from a high speed printing press
having a rotary delivery mechanism, the
45 combination with delivery mechanism, of
means in the path of travel of the sheet for
abruptly checking sheet advance by the de-
livery mechanism, said means being ren-
dered active when the sheet is released from
50 its held position in said mechanism to tend
to reverse the direction of sheet travel, a
support for the released sheets, said support
being spaced from the delivery mechanism
a distance sufficient to normally prevent set-
tling of one sheet to its supported position
55 by flotation in advance of release of the
succeeding sheet from said mechanism,
whereby more than a single sheet will be
concurrently floating toward the support,
and jogging mechanism operative on un-
60 alined sheets and positioned to permit ac-
tivity on the several floating sheets concur-
rently, whereby each unaligned sheet will be
subjected to more than a single jogging
movement in traveling from the delivery
65 mechanism to position on the support.
11. As a means for alining the sheets de-
livered from a high speed printing press
having a rotary delivery mechanism, the
70 combination with delivery mechanism, of
means in the path of travel of the sheet for
abruptly checking sheet advance by the de-
livery mechanism, said means being rendered
active when the sheet is released from its
75 held position in said mechanism to tend to
reverse the direction of sheet travel, a sup-
port for the released sheets, said support being
spaced from the delivery mechanism a
distance sufficient to normally prevent set-
80 tling of one sheet to its supported position
by flotation in advance of release of the suc-
ceeding sheet from said mechanism, where-
by more than a single sheet will be concur-
rently floating toward the support, and jog-
ging mechanism operative on unaligned sheets
85 and positioned to permit activity on the sev-
eral floating sheets concurrently, whereby
each unaligned sheet will be subjected to more
than a single jogging movement in traveling
from the delivery mechanism to position on
90 the support, said support being inclined
downwardly away from the advance end of
the sheet.
- In testimony whereof we have hereunto
set our hands in presence of the subscribing
witnesses.
